TENSION CONTROLLING MEANS FOR TRAVELING OFFSET WEBS

Application filed January 2, 1930. Serial No. 417,898.

In multicolor web perfecting presses where a traveling offset web is led around the impression cylinder of the second printing unit under the printed web, it has been difficult to 5 obtain clean and sharp printing.

I have discovered that if the tension on the offset web necessary to the proper rewinding thereof be eliminated where the offset web is in contact with the impression cylinder of the second printing unit, thus permitting the offset and printed webs to travel together around the impression cylinder, clean and sharp printing will be obtained.

To accomplish this I provide the following means located between the second printing unit and the offset web rewinding mechanism:—

First, a guide roller for taking the offset web away from the impression cylinder under the same tension as the printed web; second, a compensating device for the offset web; and third, an offset web tension controlling mechanism through which the offset web is passed and given sufficient tension to 25 produce a perfect roll in the rewinding mechanism.

In practice, the travel of the printed web per cylinder revolution varies with the different forms used on the form cylinders, 30 thus making it next to impossible to properly proportion the guide rollers of the offset web tension controlling mechanism so that they will travel with the offset web under all conditions. It is to prevent this variation from disturbing the offset web that I interpose a compensating device between the positively driven roller for taking the offset web away from the impression cylinder and the offset web tension controlling mechanism.

As it is quite difficult to proportion the guide rollers of the offset web tension controlling mechanism so that they will feed the offset web to the rewinding mechanism within the range of the compensating device, a 45 variable speed drive is employed for the offset web tension controlling mechanism.

A practical embodiment of my invention is represented in the accompanying drawings, in which

Fig. 1 represents a diagrammatic side ele-

vation of that portion of a multi color web perfecting printing press which embodies my invention; and

Fig. 2 represents a detail top plan view, showing the variable speed drive unit for 55 the offset web tension controlling mechanism.

The form and impression cylinders of the second printing unit are denoted by 1, 2, 3, 4, 5. The traveling printed web is denoted by 6 and the traveling offset web by 7, which offset web is shown as leading from the supply roll 8 around the impression cylinder 5 to the take-up roll 9 of the offset web rewinding mechanism. This rewinding mechanism, in the present instance, is shown as comprising 60 a pair of rollers 10, 11, driven from the gear 12 on the shaft of the impression cylinder 5 through the train of gears 13, 14, 15, 16, 17, 18, 19, 20, 21.

The offset web tension controlling mechanism is shown herein as comprising a plurality of guide rollers 22, 23, 24, around which the offset web is passed on its way from the second printing unit to the rewinding mechanism. These guide rollers are connected through gears 25, 26, 27.

A variable speed drive of any well known or approved form is provided for driving the web guide rollers 22, 23, 24 of the offset web tension mechanism, the one represented herein being the well known "Reeves" drive in which the shaft 28 is driven at a constant speed by the meshing of its gear 29 with the gear 19 of the train of gears leading from the second printing unit to the offset web rewinding mechanism. The shiftable cone pulleys 30 on the constant speed shaft 28 drive the shiftable cone pulleys 31 on the shaft 32 which is coupled to the shaft of the roller 22 of the offset web tension controlling mechanism, through the usual belt 33. The manually operated means for varying the speed of the shaft 32 is denoted as a whole by 34.

The printed web and the offset web are 95 taken off from the impression cylinder 5 at the same tension by providing the printed web guide roller 35 and the offset web guide roller 36. The guide roller 35 is driven from the gear 15 through the gear 37 and the guide

roller 36 is driven from the gear 15 through the gear 38, 39, 40.

The offset web compensating device is shown as comprising a gravity operated take-up roller 41 mounted in a swinging support 42 and resting upon the offset web between the guide roller 36 and the roller 22 of the offset web tension controlling mechanism.

If the travel of the rollers 22, 23, 24 of the offset web tension controlling mechanism is slow, the offset web is threaded with a slight slack with the compensating roller 41 occupying the position shown in full lines thereby allowing the roller to maintain its pressure on the web as the slack increases. If the travel of the said rollers 22, 23, 24 of the offset web tension controlling mechanism is fast, the offset web is threaded with a considerable slack with the compensating roller 41 occupying the position shown in dotted lines thereby allowing the roller to maintain its pressure on the web as the slack decreases.

As it is quite difficult to proportion the rollers 22, 23, 24 of the offset web tension controlling mechanism so that they will feed the offset web to the rewinding mechanism within the range of the compensating roller 41 it is desirable to use the variable speed drive unit for the said rollers. As has hereinbefore been explained, the constant speed shaft 28 of the variable speed drive unit is driven from the gear 19 while the variable speed shaft 32 of said unit is coupled to the shaft of the roller 22 of the offset web tension controlling mechanism. By the use of this variable speed drive it is not necessary to hold the diameters of the rollers 22, 23, 24 to such a close limit as when they are driven directly from the train of gears which connects the second printing unit with the offset web rewinding mechanism. By the use of this variable speed drive excess slack in the web between the rollers 36 and 22 can be removed by manually increasing the speed of the rollers 22, 23 and 24 or if any undue tension develops in the web at this point it can be eliminated by manually decreasing the speed of the said rollers. It is, of course, to be understood that the rewinding mechanism is geared to rewind the offset web at whatever speed it is fed to them by the web tension controlling mechanism.

The above described arrangement causes the offset and printed webs to travel together around the impression cylinder and thereby ensures clean and sharp printing on the printed web.

It is evident that various changes may be resorted to in the construction, form and arrangement of the several parts without departing from the spirit and scope of my invention; hence, I do not intend to be limited to the particular embodiment herein shown and described, but

65 60 65 70 75 80 85 90 95 100 105 110 115 120 125 130
c5 What I claim is:—

1. In a multicolor web perfecting printing press, a printing unit, a traveling offset web, an offset web rewinding mechanism, a web tension controlling mechanism therefor, a variable speed drive for the web tension controlling mechanism, and a web compensating device located between the printing unit and web tension controlling mechanism.

2. In a multicolor web perfecting printing press, a web printing unit, a traveling offset web, an offset web rewinding mechanism, means for taking the offset web away from the printing unit under the same tension as the web printed thereby, an offset web tension controlling mechanism for the rewinding mechanism, and a variable speed drive for the web tension controlling mechanism.

3. In a multicolor web perfecting printing press, a web printing unit, a traveling offset web, an offset web rewinding mechanism, means for taking the offset web away from the printing unit under the same tension as the web printed thereby, an offset web tension controlling mechanism for the rewinding mechanism, a variable speed drive for the web tension controlling mechanism, and an offset web compensating device located between the printing unit and the offset web tension controlling mechanism.

4. In a multicolor web perfecting printing press, a printing unit, a traveling offset web, an offset web rewinding mechanism, a train of gears connecting the printing unit and rewinding mechanism, a web tension controlling mechanism for the rewinding mechanism, and a variable speed drive unit connecting said train of gears with the web tension controlling mechanism.

5. In a multicolor web perfecting printing press, a printing unit, a traveling offset web, an offset web rewinding mechanism, a train of gears connecting the printing unit and rewinding mechanism, a web tension controlling mechanism for the rewinding mechanism, a variable speed drive unit connecting said train of gears with the web tension controlling mechanism, and an offset web compensating device located between the printing unit and the web tension controlling mechanism.

In testimony, that I claim the foregoing as my invention, I have signed my name this 30th day of December, 1929.

HOWARD M. BARBER.
